JOHN LUNDIE, OF NEW YORK, N. Y.

RAIL-ANCHOR.

1,350,321.

Specification of Letters Patent. Patented Aug. 24, 1920.

Application filed November 17, 1919. Serial No. 338,521.

To all whom it may concern:

Be it known that I, JOHN LUNDIE, a citizen of the United States, residing at New York, N. Y., have invented certain new and 5 useful Improvements in Rail-Anchors, of which the following is a specification.

This invention relates to improvements in anchors for the prevention of creeping of railroad rails.

10 The idea has hitherto been prevalent that a rail anchor must not only grip the rail but must abut against the tie. As a matter of fact, unless a tie is well supported by ballast on the side opposite to that on which 15 the rail anchor abuts, there is a tendency to displace such a tie, this tendency increasing in proportion to a decreasing resistance. It is true that one anchor may be placed to resist creeping in one direction while another is placed so as to resist creeping in the opposite direction, and thus one of 20 these two anchors is inoperative while the other is resisting creeping in a given direction.

25 One of the objects of the present invention, at least in its preferred form, is to provide a rail anchor which will resist the creeping of the rail in both directions. Another object of the invention is to provide 30 a simple, practical and efficient rail anchor, for accomplishing some or all of the objects which appear herein, or other objects which may not be specifically stated but which will become apparent to skilled engineers in the art from the practical use 35 of the invention.

These being among the preferred objects of the invention, the same consists of certain features of construction to be herein- 40 after specifically described and then claimed with reference to a preferred embodiment of the invention illustrated in the accom- 45 panying drawings, in which,

Figure 1 is a transverse section of a railroad rail showing the present improved anchor applied thereto;

Fig. 2 is a transverse section on the line 2—2, Fig. 1; and

Fig. 3 is a section on the line 3—3, Fig. 1, 50 showing the improved rail anchor in use, that is to say, the ties and ballast are conventionally represented to attain that end.

Referring to the drawings, the rail anchor preferably comprises two anchor mem- 55 bers 10, 11, and these members are prefer-

ably similar to each other so as to form twin members, thereby constituting a duplex anchor as it were. Inasmuch as when two of the anchor members are preferably employed, one of them will act similarly to the other, and hence a description of one member will apply equally to the other, the present specific description of parts will be confined to a single member.

Anchor member 10 or 11 comprises a web 65 or blade-like portion 12, which is of considerable height and width as clearly shown in Fig. 1, but each is comparatively thin as is apparent from the other figures. Preferably each web or blade-like portion 12 70 will have an upper and, preferably, outwardly slanting edge 13. Preferably also member 10 or 11 is provided with a neck 14 which is offset from the edge 13 and extends upwardly from the outer edge of the web or 75 blade 12.

Preferably this neck 14 merges into an inwardly extending jaw 15 which overhangs the web or blade 12. The inner end of the jaw 15 is preferably formed of a somewhat 80 spheroidal shape or in the shape of an oblate spheroid, so as to provide a spheroidal rail engaging or bearing surface 16. The curvature of the surface 16 is in a direction transverse of the rail, but the shape of the 85 under surface of the engaging end of the jaw will likewise have a semi-elliptical engaging surface 17 which extends transversely of the engaging end of the jaw, all for a purpose to be hereinafter stated. A 90 reversely curved surface 18 extends from the spherical surface 16 and joins with a curved surface of a jaw 19 which opposes the curved surfaces 16, 17. The engaging surface of the jaw 19 is rounded similarly to 95 the spheroid surface of the jaw 15 and the curved surface of the jaw 19 is compounded with the curve of the curved surface 18, so that in the preferred embodiment of the invention complementary curved surfaces 100 are provided for the jaws 15 and 19. All of the above described parts are in one vertical plane.

The web or blade-like portion 12 is preferably formed with a recess or depression in 105 one face thereof which extends from a line adjacent the outer edge of the portion 12 to the opposite edge thereof. Inasmuch as the anchor member 10 or 11 is preferably formed of a malleable casting, it may be 110

desirable to provide means for reinforcing the same. To this end the web or blade-like portion 12 is provided with substantially parallel reinforcing ribs 21, 22, which extend vertically from the lower edge of the portion 12 through a considerable distance of the height of the said portion 12, and these ribs are formed on opposite sides of the portion 12 near the outer edge thereof along lines where possibly greater stresses may have to be taken up by said portion 12. Also substantially parallel horizontal reinforcing ribs 23, 24 extend along that face of the portion 12 which is provided with the vertical rib 22, said ribs 23, 24 commencing at the rib 22 and terminating at the inner edge of the portion 12.

At a place intermediate of the ribs 23, 24 the web or blade-like portion 12 is provided with a slot or aperture 25 which extends horizontally of the portion 12 in substantial parallelism with the horizontal ribs 23, 24. The material around the aperture 25 is preferably reinforced as by bosses 31, to also provide raised seats for the washers of the connecting bolt which is to pass through said aperture. Above the aperture 25 the web or blade-like portion 12 is provided with a bore or hole 28 which extends horizontally thereof, preferably at a point not much below the jaws 15 and 19. This hole 28 is for the purpose of receiving a bolt, and it extends transversely of the direction in which the aperture 25 extends through the thickness 35 of the web or blade-like portion 12, for a purpose to be described.

Preferably the described features of each anchor member are embodied in an integral structure, somewhat in the nature of a more or less flattened, specially constructed metal plate, except that where connecting, bearing or engaging surfaces are formed the portions of the anchor member at these parts is preferably thicker than the remainder. It will be observed that under the preferred construction of the invention, the spheroidal jaws 15 and 19 are provided with rail engaging or bearing faces which are rounded transversely, such engaging surfaces being semi-elliptical in cross-section, and being arranged complementary to each other, thus providing a symmetrical relationship between the rail engaging and bearing surfaces of the two jaws of each anchor member, and providing a minimum area of contact in all vertical planes of the anchor. The gap or mouth between the engaging and bearing surfaces of the jaws 15 and 19 is so proportioned that it will have sufficient height to enable the said gap or mouth to receive one of the side flanges of the base of the rail, such as R. Preferably the closest approach of the rail bearing surfaces of the jaws 15 and 19 is at points coincident with an imaginary vertical line lying in the central vertical plane of the

rail anchor member. Such being the case, the opposite curved or rounded surfaces of the jaws 15 and 19 will gradually diverge from each other in opposite directions away from the central vertical plane or cross-section of the transverse gap or mouth between the jaws for a purpose to be hereinafter stated.

Although one of the described anchor members or its equivalent may engage with the base of the rail at one point along the line of the rail, while another anchor member such as described may engage the rail at another point along its length, it is preferred to assemble two anchor members, so as to provide a twin or duplex anchor to engage the rail at the opposite flanges of its base. To this end the anchor members are mated, that is to say, the recesses or depressions 20, if they are formed in said members, are caused to face each other by first overlapping the two anchor members so that the jaws of each member will be placed in opposition to the other, that is, so that the mouths or gaps between them will open toward each other, or at least with the members so overlapped that the jaws will extend as stated; the overlapping portions of the webs or blades 12 are placed in contact with each other so as to register the aperture 25 in one anchor member with that in the other. A bolt 26 is then passed through the registering apertures 25, 25 and a nut 27 is engaged with the threaded end of the said bolt, and the nut tightened up sufficiently to hold the two members together. Likewise a bolt 29 is passed through the registered holes 28, 28 in the two anchor members, and a nut 30 turned onto the threaded end of said bolt. It will be seen that in the preferred embodiment of the invention the bolt 26, passing only through the thickness of the anchor, will be much shorter than the bolt 29, and that the two bolts will be disposed substantially at right angles to each other, for the preferred method of tightening the anchor and holding it on the rail. When anchor members of the described construction are placed together, it will be seen that the depressions or recesses 20 in each member will receive the web or blade of the other member, when the bolt 26 is sufficiently tightened, and that thus the longitudinal axis of the bolt 29 will extend in a plane which intersects the preferably shorter bolt 26 at about its mid-length.

Preferably the described anchor is so constructed as to engage with the opposite side flanges of the rail base, and such a rail anchor being provided with the parts assembled by means of the bolt 26, it is but necessary in applying the anchor to the rail to move the blades or webs 12 along each other and to preliminarily engage the jaws of the two members with the opposite

flanges. Before this preliminary adjustment to the rail takes place it will, of course, be necessary to remove some of the ballast between the ties so that the anchor may be positioned properly. When the anchor has been applied to the base by adjusting it through the medium of the bolt 26, if left free, gravity will hold it in a vertical plane intersecting the rail R at right angles. This 10 may be assumed to be the normal position of the anchor on the rail except that the anchor has not as yet been tightened up to the rail. Bolt 29 is now inserted through the alined holes 28, 28 and the nut 30 secured thereon; the nut being tightened up sufficiently so as to move the jaws of the two members of the anchor toward each other, and to cause them to bite more or less upon the base flanges of the rail. Preferably the 20 position of the anchor will be such as to be free of the ties. Ballast is now placed in around the anchor and is well packed opposite the blades and in the line of the rails between succeeding ties. The ballast will, 25 of course, so hold the anchor that it can yield within proper limits due to the creeping of the rail.

The rail anchor of the preferred construction will consist of two identical or similar 30 parts so designed that they will not only interact in gripping a rail tightly, but what is more important, will interact so that the resistance to rail creeping will be offered by both parts of the anchor at the same time. It 35 will be seen that when the rail tends to creep, the grip of the jaws tightens gradually in accordance with the increased creep of rail, and inasmuch as the bearing and gripping surfaces of the jaws are formed preferably as 40 described, an easy adjustment is given not only in placing the anchors on the rail, in the first place, but in presenting round faces to the upper and lower surfaces of the rail base, and so adjusting little inaccuracies of bearing. Bearing and rolling surfaces such as 45 described prevent nicking of the rail base, which might impair the efficiency of the rail tending toward breakage thereof. The comparatively large blades depending in the bal- 50 last, present interacting resisting surfaces to the ballast, which resistance passes through the ties to the adjacent ballast. The anchor partakes of an angular movement in both directions of the creep of the rail, and the 55 reverse, symmetrically disposed, curved surfaces of the jaws rolling, as it were, on the opposite surfaces of the base flanges of the rail establish a force couple, which acts the greater the more the anchor is tipped from 60 its normal vertical plane, which has been explained to be that plane which the anchor would be caused to take by gravity when left free to hang on the rail and before the anchor is tightened up and the ballast re- 65 placed. As the transverse gaps or mouths

between the jaws are defined by curved surfaces which are preferably of semi-elliptic cross-section, and as the said surfaces flare symmetrically outward from the central vertical plane of the anchor, it is apparent that 70 when the rail gradually creeps in one or the other direction, the anchor is gradually tipped through an ever increasing angle, and the greater the extent of creep the greater the angle, so that the curved jaw surfaces 75 tend to pinch upon the base flanges with ever increasing tenacity.

The described invention is obviously susceptible of a wide range of modification, whether or not a single anchor member is 80 used by itself or two members are assembled for mutual interaction, and it is clear that the two members when assembled may be assembled by different means and in different ways, and that they may be differently constructed, all without departing from the spirit and scope of the invention as expressed in the claims.

What I claim as new is:

1. A rail anchor, comprising, in combination, means for gripping the rail in either direction of its creep, and anchorage means therefor for engagement only with the ballast, whereby, owing to the tendency of the creep of the rail to overcome the resistance 95 of the ballast, the entire anchor is rocked and said gripping means is caused to automatically tighten its grip on the rail.

2. A rail anchor, provided with means for automatically gripping the rail, by the 100 influence of the creep of the rail in either direction, said anchor comprising two substantially identical ballast-engaging members.

3. A rail anchor, provided with means 105 for automatically gripping the rail, by the influence of the creep of the rail in either direction, said anchor comprising twin ballast-engaging blades.

4. A rail anchor, provided with means 110 for automatically gripping the rail, by the influence of the creep of the rail, said anchor comprising twin, overlapping, roadbed-engaging blades.

5. A rail anchor, provided with means 115 for automatically gripping the rail, by the influence of the creep of the rail, said anchor comprising two substantially identical roadbed-engaging members having spheroidal rail-base gripping jaws.

6. A rail anchor, comprising spheroidal jaws for gripping the opposite side flanges of the rail-base with a minimum area of contact in all vertical planes of the anchor, and means for tightening the grip by the 125 action of the creep of the rail, the contact points of said jaws being located substantially in the vertical plane of said means.

7. A rail anchor, comprising means for gripping the opposite side flanges of the 130

- 5 rail-base, and interacting means proportioned for depending for a substantial depth into the ballast, for tightening the grip by the action of the creep of the rail in either direction.
- 6 8. A rail anchor, comprising jaws for engaging the rail, and web or blade-like bridging means extended for a considerable distance downwardly with respect to said jaws 10 for obtaining a substantial depth of anchorage in the ballast.
- 15 9. A rail anchor, comprising spheroidal jaws for engaging the rail, and bridging means extended for a considerable distance downwardly with respect to said jaws for 15 obtaining a substantial depth of anchorage in the ballast.
- 20 10. A rail anchor, having spheroidal jaws, arranged in substantially symmetrical relationship, for gripping opposite flanges of the rail-base.
- 25 11. A rail anchor, comprising substantially identical members, formed for engagement with the opposite flanges of the rail-base, the lower portions of said members being arranged to press upon each other when the rail creeps in either direction.
- 30 12. A rail anchor, comprising similar members, for embedment in the ballast out of contact with the ties, and having rail-base gripping portions, said members being 35 mutually opposed in the direction of the creep of the rail to obtain interaction of said members in either direction, and each of said members being at least substantially as wide as the rail, so as to extend for a substantial distance under the rail, and means for clutching and securing said gripping portions upon the rail.
- 40 13. A rail anchor, comprising mutually opposed, similar, plate-members, for embedment in the ballast, having rail-base gripping portions, and being placed flatwise against each other so as to overlap, said 45 plate-members being separable transversely thereof, and means for clutching and securing said gripping portions upon the rail.
- 50 14. A rail anchor, comprising similar members, for embedment in the ballast out of contact with the ties, and having rail-base gripping portions, and said members being 55 mutually opposed in the direction of the creep of the rail to obtain interaction of said members in either direction, a fastening connecting the lower ends of said members and permitting the transverse separation of said members, and means for clutching and securing said gripping portions upon the rail.
- 60 15. A rail anchor, comprising similar plate-members for embedment in the ballast and for biting upon the rail.
16. A rail anchor, comprising similar members for embedment in the ballast and

for biting upon the rail, said members overlapping one another.

17. A rail anchor, comprising similar members for embedment in the ballast and for biting upon the rail, said members overlapping one another, and being positively connected together at two points of each of them.

18. A rail anchor, comprising mutually opposed members, each of which is at least substantially as wide as the rail, said members having rail-base gripping jaws, and being materially extended below the jaws and overlapping each other for a substantial portion of their area in a plane at approximately right angles to the rail.

19. A rail anchor, comprising twin rail-base gripping members, having road-bed engaging portions, free from engagement with the ties, and arranged to mutually interact and bear one upon the other.

20. A rail anchor, comprising twin rail-base gripping members, having opposed faces for extending transversely of the rail, and each of which is arranged to act in the direction of the other and upon it.

21. A rail anchor, comprising two rail-base gripping members having road-bed engaging portions, free from engagement with the ties, and arranged one of said portions directly in advance of the other for mutual interaction.

22. In a rail anchor, in combination, a pair of members for conjointly engaging the rail and the ballast, means for holding them in assembled using position, and additional means for fixing them in a clamping position upon the rail.

23. In a rail anchor, in combination, a pair of substantially identical blade-like members for conjointly engaging the rail and the ballast, means for holding them in assembled using position, and additional means for fixing them in a clamping position upon the rail.

24. In a rail anchor, in combination, a pair of members for conjointly engaging the rail and the ballast, means for adjustably holding them in assembled using position, and additional means for fixing them in a clamping position upon the rail.

25. In a rail anchor, in combination, a pair of members for conjointly engaging the rail and the ballast, means for holding them in assembled using position, and additional means for fixing them in a clamping position upon the rail, the combined means comprising bolts arranging in angular relation with respect to each other.

26. In a rail anchor, an integral member having spheroidal jaws, arranged in substantial symmetry to engage the rail, said member being of blade or plate-form of considerable breadth and height beneath said

jaws and disposed in approximately the plane of the contact surfaces of said jaws transversely of the rail.

27. In a rail anchor, a member comprising means to engage the rail and means to engage the roadbed, said member having bolt-holes arranged one above the other in angular relation.

28. In a rail anchor, a member comprising means to engage the rail and means to engage the roadbed, said member having

bolt-holes arranged one above the other in angular relation, the upper hole being considerably longer than the lower one.

29. A rail holding member of a rail anchor, consisting of an elongated and relatively wide ballast-engaging plate-portion provided with a bolt-hole width-wise thereof, and rail-base engaging jaws above said hole. 15

JOHN LUNDIE.
